UNITED STATES PATENT OFFICE.

CHARLES D. P. HAYCRAFT, OF FELLOWSHIP, FLORIDA.

WIRE-STRETCHER.

No. 836,445.

Specification of Letters Patent.

Patented Nov. 20, 1906.

Application filed August 28, 1905. Serial No. 276,089.

to all whom it may concern:

Be it known that I, CHARLES D. P. HAYCRAFT, a citizen of the United States, residing at Fellowship, in the county of Marion, State 5 of Florida, have invented a new and useful Wire-Stretcher, of which the following is a specification.

This invention relates to improvements in wire-stretchers, and has more particular reference to a device of this class that is especially adapted for use in the construction of woven-wire fences, as well as other kinds of wire fences.

The object of the present invention is to 15 improve the construction of wire-stretchers and to provide a simple and strong one adapted to be readily attached to a fence-post, compact, but powerful enough to stretch the heaviest woven-wire fence now 20 in use.

The invention consists in the construction and novel combination and arrangement of parts hereinafter fully described, illustrated in the accompanying drawings, and pointed 25 out in the claims hereto appended.

In the drawings, Figure 1 is a horizontal view of wire-stretcher constructed in accordance with this invention, showing the wire-stretcher attached to fence-post and in working 30 position. Fig. 2 is a side elevation of the same. Fig. 3 is end elevation showing operating-lever and post-fastening device. Fig. 4 is a sectional end view showing double-spaced bars and segments, ratchet-bar, hook of operating-pawl, locking-pawl, and springs on 35 rolled shoulders of locking-pawl.

Like letters of reference indicate like parts in all figures of the drawings.

Referring more particularly to the drawings, A A are double-spaced bars held apart by space-lugs a a a, riveted or bolted together, having curved arms, and to the middle of the straight portion of the bars and on the outside of each bar is riveted a segment. 40

In the arms of the double-spaced bars, between bars and space-lugs, is T-shaped drive-dog E, slotted for bolt, which holds the same 45 into its place.

At the open end of and between double-spaced bars A A is pivoted curved bar F, notched on the outer edge, on which slides the adjustable drive-dog G, slotted for the said curved bar, with sliding catch g. Pushing the sliding catch g into any notch in the 50 curved bar F makes the adjustable drive-dog G stationary on the said bar at that point.

Between double-spaced bars A A is the ratchet-bar D, movably mounted on two pivoted rollers H H. (Shown in Fig. 1 by dotted circles.)

Fastened to the ratchet-bar D by the lap-link L is wire-engaging clamp W. On operating-lever is pivoted a spring x, hand-lever b, connected by a rod c to a flanged hook-operating pawl C, carried by operating-lever B, 65 which is fulcrumed near one end on the pivoted roller H. Pressing on hand-lever b causes operating-pawl C to engage the teeth in ratchet-bar.

The two yoke-shaped locking-paws R R, 70 working on outside of double-spaced bars, are pivoted on the same pivot as the rollers H H. These pawls have at each end outwardly-extending integral tubular sleeves or shoulders R' R', which form extended bearings on the 75 bolts H' H'. The locking-paws are automatically held against ratchet-bar by springs S S, which are fastened to outside of bars A A, working around the sleeves R' R' and fastened to thumb-catches T T. Thumb-catches are used to raise locking-paws out of 80 notches in the ratchet-bar. The stationary wire-engaging clamp Z on bar is used to hold wire while splicing and is not used when stretcher is attached to post. The keys K K 85 are used to hold locking-paws clear of ratchet-bar.

To operate the device, the locking-paws R R are thrown back and locked by keys K K and the ratchet-bar D pulled out until 90 stopped by stop-pin in bar. Push keys K K out of notches in locking-paws and let the pawls R R down on ratchet-bar D. If barb or cable wire is to be stretched, use wire-engaging clamp W. If woven wire is to be 95 stretched, remove wire-engaging clamp W from lap-link L and insert in lap-link a plow-clevis. Fasten the plow-clevis around the center of wooden clamp that has been bolted to woven wire. Pull wire-stretcher back until curved arm can slip by post. Then let the arm rest solidly against the post. Drive dog 100 E into post and move adjustable drive-dog G where desired on bar. Push the sliding catch g on drive-dog G into notch of curved bar F 105 and push said bar around until point of drive-dog G touches the post and drive the drive-dog G into the fence-post. Push operating-lever back toward the fence-post to which stretcher is attached, press on the hand-lever b until it forces hook of operating-pawl C 110 down into the notch of ratchet-bar D, then

pull operating-lever B toward wire being stretched. The locking-pawls R R will make a clicking sound as the pawls drop down into the notches of ratchet-bar D, and 5 pawls will prevent any reverse movement of the ratchet-bar. Repeat the operation with operating-lever B and hand-lever b, holding both levers during the pulling until the wire is taut.

10 The invention has the following advantages: The wire-stretcher possesses great strength and durability by having double-spaced bars, each bar and curved arm being one solid piece. The curved arm of stretcher 15 with drive-dog and a pivoted curved bar with an adjustable drive-dog makes a strong post-fastening readily attached to any post. The segments being an arc makes it the strongest frame that can be devised upon 20 which an operating-lever can be fulcrumed. The operating-lever being fulcrumed on pivoted roller between segments makes it easier to operate and gives the lever greater wearing-surface at its fulcrum. The operating-pawl is 25 not dependent on a coil-spring or gravitation for its action; but the pawl being connected by a rod to hand-lever pivoted to operating-lever makes the action of operating-pawl positive by pressure on hand-lever. The two automatic locking-pawls divide the strain caused 30 by tension on wire equally between them. If for any reason one of the locking-pawls should fail to work, the other pawl will engage the ratchet-bar and prevent reverse movement of the bar. If for any reason one 35 of the locking-pawl springs should fail, the other spring on the opposite side of the pawl will force the pawl into the notch in ratchet-bar, thus locking it.

40 It is evident that many changes may be made in the construction and arrangement of the parts in my device, and I claim all such as come within the scope of my invention.

Having fully described my invention, I 45 claim the following as new and desire to secure Letters Patent therefor:

1. In a wire-stretcher, comprising double-spaced bars A A, a segment riveted to the middle of the straight portion of and on the 50 outside of each bar, each bar having a curved arm, the bars being held apart by spacing-lugs a a a and rigidly bolted together to form the frame of the stretcher, substantially as described.

55 2. In a wire-stretcher, the combination with parallel curved frame-bars, spacing-lugs between bars, and securing means passed

through bars and lugs, the curved portion of the bars, adapted to receive a fence-post, a post-engaging T-shaped drive-dog E mounted in the curved portion of the bars, a slot in the dog, a bolt through the slot and bars, a curved bar F pivoted between the frame-bars and notched in its outer edge and a post-engaging drive-dog G adjustable on the bar 65 and having a catch g adapted to be pushed into any notch in the bar to make the dog stationary on the said bar, substantially as described.

3. In a wire-stretcher, in combination, a 70 frame comprising parallel bars, spacing-lugs between the bars, bolts passed through bars and lugs, a post-engaging means pivoted between the parallel bars, rollers H H journaled in said bars on bolts H' H', the toothed 75 ratchet-bar D movable on the rollers, a wire-clamp W connected to the ratchet-bar, means for actuating bar and means for locking the said bar, substantially as described.

4. In a wire-stretcher, the combination of 80 parallel spaced bars forming a guideway, a post-securing means connected to the bars, rollers journaled in the bars, a ratchet-bar movable on the rollers, segments secured to the bars carrying a roller H, an operating-lever 85 B fulcrumed on roller H, a flanged operating-pawl C pivoted to the lever and arranged to engage the ratchet-bar, a spring-actuated hand-lever b on the lever B, a rod c connecting the pawl and hand-lever and 90 means for locking the ratchet-bar, substantially as described.

5. In a device of the class described, the combination of spaced bars forming a guideway, a post-securing means connected to the 95 bars, rollers journaled in the bars, a ratchet-bar movable on the rollers, segments secured to the bars and having a roller journaled therein, an operating-lever fulcrumed on the roller, and having a yoke-shaped end, a 100 spring-actuated hand-lever on the operating-lever, a flanged pawl pivoted in the yoke end of the operating-lever to actuate the ratchet-bar, a rod connecting the pawl and hand-lever, yoke-shaped locking-pawls R R pivoted 105 to the spaced bars on bolts H' H' and engaging the ratchet-bar and springs S S S S normally holding the last-mentioned pawls in operative position substantially as shown and described.
